UNITED STATES PATENT OFFICE.

FREDERICK WALTER DENNIS, OF ATLANTA, GEORGIA, ASSIGNOR OF ONE-HALF TO JAMES FRANKLIN LESTER, OF SAME PLACE.

GARBAGE CREMATOR OR CALCINER.

SPECIFICATION forming part of Letters Patent No. 631,457, dated August 22, 1899.

Application filed August 5, 1898. Serial No. 687,863. (No model.)

To all whom it may concern:

Be it known that I, FREDERICK WALTER DENNIS, a citizen of the United States, residing at Atlanta, in the county of Fulton and State of Georgia, have invented certain new and useful Improvements in Continuous Garbage Cremators or Calciners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention is a continuous self-burning garbage cremator or calciner constructed to burn garbage, animal matter, and the like and at the same time to consume and destroy the odors and smoke arising therefrom and 20 may be used for drying minerals, ores, clays, and other substances, each furnace and its auxiliary furnace being provided with a flue leading to one main central stack and a cut-off, said cut-offs and flues so arranged that 25 the heat may be carried from each furnace and its auxiliary to the next until the entire circuit of the cremator is made. Any number of furnaces and chambers may be arranged to use one smoke-stack.

30 In the accompanying drawings, Figure 1 is a front elevation of my cremator with the front partly broken away and the framework above the brickwork removed. Fig. 2 is a horizontal sectional view of Fig. 1 cut on the line *y y* of Fig. 1. Fig. 3 is a vertical sectional view cut on the line *x x*, as indicated in Fig. 2. Fig. 4 is a vertical sectional view, as indicated by the line *z z* of Fig. 2.

35 In the accompanying drawings, A B C D are furnaces, and *a b c d* are their auxiliaries, respectively. Each furnace A B C D and *a b c d* is provided with doors and a fire-box 1, and each fire-box is provided with grate-bars 2. These grate-bars rest on walls constructed of 40 stone, fire-brick, or other fireproof masonry. Extending from the forward end of these 45 grate-bars 2 in furnaces A, B, C, and D are arches 3, and beyond the arches 3 are the flame-pits 4, inclosed in walls 5, 6, 7, and 8. 50 (See furnace C, Fig. 2.) The brick floors between the flues are on a level with the gar-

bage-bars. The center walls 6, the right-hand walls 7, and the end walls 8 are provided with perforations 9, so that heat from the starting-furnace—say, furnace A—passes under 55 garbage-bars 20, and then passes partly through perforations in walls 6 and 8 into flame-pocket 10 and passage 11, thence along flue 12, thence through and over the garbage to the left into flue 13, thence under arch 14 60 into flue 15, thence under and through grates 16 and through auxiliary furnace *a*, in which charcoal, coke, or smokeless coal is burned to consume odors and smoke, (by the combustion of which great heat is obtained for 65 drying and heating garbage in next chamber B,) thence, if cut-off 18 is open, along flue 17 into smoke-stack 19, and thence upward into the elements above; but if cut-off 18 between furnaces A and B is closed then the heat and 70 flames will go along flue 15 into furnace B, and thenceforth they will take the same course through furnace B that they did in the first instance through furnace A, and if cut-off 18 between furnaces B and C is open the heat 75 and flames will go along flue 17 between B and C to smoke-stack 19. If all the cut-offs 18 are closed except the last in the circuit, the heat and flame will pass through all the furnaces and chambers, thence to smoke- 80 stack 19 through the last open cut-off 18. Thus it will be seen that I can run one furnace with its auxiliary or I may run two or more furnaces with their respective auxiliaries with one fire in the initial or beginning 85 furnace. By passing the heat around from chamber to chamber, as above described, I dry the garbage before burning and use it as fuel. When the garbage in the first or initial chamber has been consumed, the doors to the fur- 90 nace of this first chamber are closed and the doors to the next or second chamber in order are opened and the garbage in this second chamber will be ignited and begin burning with little or no additional fuel or combustible matter. This process will be continued 95 around the entire circuit, and the first chambers burned down will be allowed to cool and the unburned or non-combustible material or matter removed before they are again loaded 100 or charged with garbage.

Resting on the walls 5, 6, 7, and 8 are gar-

bage-bars 20, of iron or some other non-combustible material, and on each of these garbage-bars are situated removable small frameworks 21, also of iron or other non-combustible material, to keep the garbage from packing.

The furnaces A B C D and their auxiliaries a, b, c, and d and ash-pits are cleared out through their outside openings or doors, but 10 to the left of each furnace, and on a line with arches 3 and garbage-bars 20 (see Fig. 3) are openings 22, through which all unconsumed matter may be drawn.

The outer walls of fire-box 1 to furnaces A, 15 B, C, and D are extended upward to top of cremator, forming fuel-chamber 35 (see Fig. 3) over the outer ends of grate-bars 2. This chamber is to receive dry or combustible garbage and is provided with a lid at the top to 20 be opened when dumping garbage into this chamber and to be closed at other times to prevent escape of smoke or odor. At the bottom of this chamber about one foot above the fire-box are two or more iron rods 36. These 25 bars are loose and serve the purpose of regulating the discharge of the garbage into the fire-box. There are perforations 34 through the walls of the main garbage-chamber into this fuel-chamber 35. These perforations ad- 30 mit steam and odors into the main garbage-chamber, where they are carried, with the smoke and flames, into the regular course of the furnace. (See Fig. 3.) This fuel-chamber is designed to provide dry combustible 35 material to supply fuel to the furnaces A, B, C, and D.

On the left of one furnace is constructed an oxygen-flue 33 on the grade-line, running from outside of main wall to base of smoke- 40 stack 19. (See dotted lines, Fig. 2, to the left of furnace A.) This is used to admit when necessary oxygen to smoke-stack for the purpose of creating additional combustion to consume such smoke or odors as have not 45 been consumed in the auxiliary furnaces. This flue will be regulated by a cut-off on the outside.

Through the top of the cremator are dumping-holes 23, one over each chamber. These 50 dumping-holes are provided with covers 24, operated by levers 25, secured to pendants 26, the lower ends of which are secured to said covers 24, said levers fulerumed in bearings 27, depending from the upper beams 28 55 of the framework on top of the cremator.

Secured to the framework and main stack are beams 29, each provided with a pulley 30. In these pulleys 30 work ropes 31, and to the 60 lower ends are attached the dampers or cut-offs 18, and by means of these pulleys, ropes, and weights said dampers are operated.

The cremator may be braced in any secure manner desired, and it may be built circular instead of square and with any number of 65 furnaces and chambers, and it may be built

to operate from left to right instead of from right to left by interchanging walls 57.

Having described my invention, what I claim as new, and desire to secure by Letters Patent, is—

1. A cremator, consisting of an outer wall and an inner wall, leaving between said walls a continuous flue 15; main furnaces A, B, C, D, to consume the garbage; each having auxiliary furnaces a, b, c, d, on a level with the 75 main furnace, to consume the odors and smoke; each main furnace having a solid wall 5, and perforated walls 6, 7, and 8, to support the garbage-bars; flame-pockets 10, passages 11, flues 12, arches 3, and garbage- 80 bars 20; flues 13 leading from main furnaces into flue 15, conducting the smoke and odors through auxiliary furnaces a, b, c, d, into flues 17; cut-offs 18, one in each flue 17, with means for feeding and cleaning out said furnaces, substantially as shown and described and for the purposes set forth.

2. A cremator, consisting of an outer wall and an inner wall, leaving between said walls a continuous flue 15; main furnaces A, B, C, 90 D, to consume the garbage; each having auxiliary furnaces a, b, c, d, on a level with the main furnace, to consume the odors and smoke; each main furnace having a solid wall 5, and perforated walls 6, 7, and 8, to support 95 the garbage-bars; flame-pockets 10, passages 11, flues 12, arches 3, and garbage-bars 20; flues 13 leading from main furnaces into flue 15, conducting the smoke and odors through auxiliary furnaces a, b, c, d, into flues 17; 100 oxygen-flue 33 leading from the outer wall, under the cremator, to the central stack, with means for feeding and cleaning out the cremator, substantially as shown and described and for the purposes set forth.

3. A cremator, consisting of an outer wall and an inner wall, leaving between said walls a continuous flue 15; main furnaces A, B, C, D, to consume the garbage; each having auxiliary furnaces a, b, c, d, on a level with the 110 main furnace, to consume the odors and smoke; each main furnace having a solid wall 5, and perforated walls 6, 7, and 8, to support the garbage-bars; flame-pockets 10, passages 11, flues 12, arches 3, and garbage-bars 20; 115 flues 13 leading from main furnaces into flue 15, conducting the smoke and odors through auxiliary furnaces a, b, c, d, into flues 17; cross-beams 29, pulleys 30, ropes 31 and weights 32 for operating cut-offs 18, substantially as shown and described and for the 120 purposes set forth.

4. In a cremation-furnace, the combination of garbage-chambers, of fuel-chambers, the walls separating the garbage and fuel chambers being provided with openings 34 and openings 22, main furnaces situated beneath and communicating with the fuel-chambers, and removable iron rods, situated between the fuel-chambers and the main furnaces, where- 130

by the gases of the fuel-chambers are permitted to escape to the garbage-chambers through openings 34 and whereby the dried garbage may be raked through openings 22 to the fuel-chambers, and then discharged into the main furnaces, substantially as shown and described and for the purposes set forth.

In testimony whereof I affix my signature in presence of two witnesses.

FREDERICK WALTER DENNIS.
